UNITED STATES PATENT OFFICE.

EMIL VON PORTHEIM, OF PRAGUE, AUSTRIA-HUNGARY.

PROCESS OF PRODUCING OXALIC ACID.

1,205,493.

Specification of Letters Patent. Patented Nov. 21, 1916.

No Drawing.

Application filed March 27, 1916. Serial No. 86,969.

To all whom it may concern:

Be it known that I, EMIL VON PORTHEIM, manufacturer, a subject of the Emperor of Austria-Hungary, and resident of Prague, in the Empire of Austria-Hungary, have invented certain new and useful Improvements in Processes of Producing Oxalic Acid; and I do hereby declare the following to be a full, clear, and exact description of the invention, such as will enable others skilled in the art to which it appertains to make and use the same.

A number of methods are known for the oxidation of sugar and other carbohydrates by aid of nitric acid or nitric oxids in the presence of catalyzers; to all of these, however, there is common a very considerable drawback, namely, that of an extremely large and spontaneous increase of temperature arising in the course of the initial stage of the process. Now while it has indeed been claimed that such a spontaneous increase of temperature may be removed by cooling, it has actually been found that this will only take place when the experiments are conducted on a small scale, and that, whensoever it is attempted to carry out the process on a large scale, such as work in a factory renders necessary, it proves impossible to remove by cooling the heat initially developed within the masses subjected to the reaction. On the contrary, the temperature will, within a short time, attain such a degree as to cause the reaction to take place with the violence of an explosion, in consequence of which not only a large portion of the sugar is oxidized to carbonic acid, but there will also suddenly arise nitrous gases in such a considerable quantity that it will be found impossible to deal with them satisfactorily. By means of my invention it is possible to uniformly distribute the said sudden development of heat over any desired length of time and thus to safely prevent the otherwise too violent reaction. What is done, is to preliminarily treat the sugar with nitrous gases in the absence of a catalyzer, before it is used for the production of oxalic acid. To this end, the dry sugar is placed, without any addition whatever, in a closed vessel, through which nitrous gases are caused to flow. The result will be that the sugar takes up nitric oxids and is thereby gradually converted into a soft or even a liquid mass; a slight development of heat taking place continuously.

The increase in the temperature of the mass, depends upon the velocity of the flow of gas, and by suitably selecting the said velocity, the temperature may be constantly maintained at any degree desired. As all risk of a rapid spontaneous increase of heat is entirely excluded, the temperature may be allowed to rise to 60° C. without impairing the yield of oxalic acid. In order to shorten the time required for the aforesaid preliminary treatment, it is advisable to cause the vessel to be cooled from without; notwithstanding the same result will be obtained in a slightly longer period of time without going to the trouble of cooling the vessel. The sugar thus preliminarily treated is hereupon employed according to any one of the known methods, in the place of the non-treated sugar, for the production of oxalic acid.

In the course of the main oxidizing process, but little or no heat will be developed, according to whether the preliminary treatment had or had not been continued until the development of the heat had been completed.

The yield of oxalic acid, calculated upon the basis of the quantity of pure sugar employed, is in no way influenced by the preliminary treatment; in other words, it is identical with that obtained when the production of the oxalic acid is effected without the aid of a preliminary treatment, that is to say, on a small scale, in the laboratory, where the cooling still proves successful.

Example I: 100 parts by weight of sugar are treated with 100 to 200 parts by weight of gaseous NO_2 , the temperature being maintained at about 30°-40° C. by suitably selecting the velocity of the flow of gas and of the degree of cooling. Hereupon, there are added 36 parts by weight of water or a quantity of nitric acid of any degree of concentration desired containing the aforesaid 36 parts by weight of water, and further, as a catalyzer, oxid of molybdenum or oxid of vanadium; whereupon further quantities of NO_2 are introduced until the formation of oxalic acid is almost complete.

The working up of the mass is carried out in such a manner that, for example, after the expulsion of the nitrous gases by aid of air, the crystals which have formed themselves are removed from the vessel, are then separated by suction or by means of centrifugal force from the mother-liquor still

clinging to them; whereupon, while the latter is again made use of as a starting liquor for a fresh reaction, the crystals are cleansed by means of re-crystallization. However, by 5 continuously passing through a strong current of air, the mixture of crystals and mother-liquor may be heated up to 50° C., in consequence of which, while, whatever portion of the carbohydrate still remaining will 10 be oxidized to oxalic acid, the nitric acid present in the said mixture will be split into nitrous gases (which escape) and water (which remains behind). As a result of the separation by centrifugal power and the re- 15 crystallization of the oxalic acid obtained in this manner, the filtrate obtained will prove to be, for all practical purposes, a solution of the catalyst free from all nitrogen compounds.

20 Example II: 100 parts by weight of sugar are placed upon a slightly inclined grid or the like, contained in the upper part of a closed vessel, whereupon 150 to 200 parts by weight of NO₂ are passed through. The 5 sugar is gradually liquefied and slowly flows off to the lower portion of the vessel. Upon the termination of this preliminary treatment, 400 parts by weight of nitric acid of a density of 40° Bé. and the required quan-

30 tity of catalyst are added to the sugar, 35 consequence of the presence of nitrous gases, which have been absorbed by the sugar, the reaction immediately commences and may be kept at a uniform rate with extraordinary facility, simply by cooling.

Example III: 100 parts by weight of sugar are treated with 150-200 parts by weight of gaseous NO₂ and are then introduced into 1000 parts by weight of a mixture of nitric acid and diluted sulfuric acid 40 containing the catalyst. The temperature is maintained at 50°-60° C., until the reaction is completed.

What I claim is:—

The process of producing oxalic acid from 45 sugar and other carbohydrates by means of nitric oxids or nitric acid and catalysts, which comprises subjecting the carbohydrates to a preliminary treatment with nitrous gases.

50 In testimony that I claim the foregoing as my invention I have signed my name in presence of two subscribing witnesses.

EMIL VON PORTHEIM.
